(57) CLAIM

The ornamental design for a baby bed, as shown and described.

DESCRIPTION

FIG. 1 is a front perspective view of a baby bed, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a top view thereof of the combined state 2;

FIG. 9 is a perspective view thereof of the combined state 1; and,

FIG. 10 is a perspective view thereof of the combined state 2.

The broken lines shown in the drawings illustrate portions of the article that form no part of the claimed design.
